US00D641784S

(12) **United States Design Patent**
Lira-Nunez et al.

(10) **Patent No.:** **US D641,784 S**
(45) **Date of Patent:** **** Jul. 19, 2011**

(54) **WRITING INSTRUMENT**

(75) Inventors: **Carmen Lira-Nunez**, Downers Grove, IL (US); **Matthew J. Gerules**, Chicago, IL (US)

(73) Assignee: **Sanford, L.P.**, Oak Brook, IL (US)

(**) Term: **14 Years**

(21) Appl. No.: **29/359,418**

(22) Filed: **Apr. 9, 2010**

(51) LOC (9) Cl. **19-06**

(52) U.S. Cl. **D19/48**

(58) Field of Classification Search .... D19/35, D19/36, 41-51, 54-58; 24/10 R, 11 CC, 24/11 F, 11 P, 11 PP, 11 R; 401/52, 99-114, 401/192, 193, 195-198

See application file for complete search history.
